EINAR BERGVE, OF CHRISTIANIA, NORWAY, ASSIGNOR TO NORSK HYDRO-ELEKTRISK
KVAELSTOFAKTIESELSKAB, OF CHRISTIANIA, NORWAY.

MANUFACTURE OF REDUCING ALKALINE MELTS.

1,354,451.

Specification of Letters Patent. Patented Sept. 28, 1920.

Application filed March 10, 1919. Serial No. 281,753.

To all whom it may concern:

Be it known that I, EINAR BERGVE, a subject of the King of Norway, of Christiania, Norway, have invented certain new and useful Improvements in the Manufacture of Reducing Alkaline Melts; and I do hereby declare the following to be a full, clear, and exact description of the invention, such as will enable others skilled in the art to which it appertains to make and use the same.

This invention relates to the manufacture of alkaline reducing melts and has for its object to produce a reducing melt having a low melting point as well as an improved process for the production of such melts.

In organic syntheses particularly for the manufacture of dyes, such as indigo, alkaline melting operations are frequently comprised in the processes, the said melting operation being effected by the use of hydroxid of potassium, to which sodium metal or sodium amid has been added. The action of the said metallic aluminium or the aluminium amid, as known, is due to the fact that the water formed is immediately removed.

In order to attain the greatest possible output it is of importance that the temperature of the melt be as low as possible.

The present invention is based upon the observation that it is possible to lower the temperature of the alkaline reducing melt below the temperature hitherto employed in connection with the use of sodium amid and at the same time to increase the reducing action. This is made possible by dissolving metallic sodium or potassium in alkali metal hydroxid preferably in an equimolecular mixture of the hydroxids of sodium and potassium.

Preferably the metal dissolved in the hydroxid consists of about one sodium to two potassium (NaK_2).

I have found that when an equimolecular mixture of sodium- and potassium hydroxids is electrolyzed with a sufficiently low current density at the cathode the separated metal immediately enters into solution again and a homogeneous melt is produced which contains the alkali metals in the proportion above stated (NaK_2).

Example I.

A melt consisting of 40 per cent. sodium hydroxid and 60 per cent. potassium hy-

droxid (melting point 167°) is electrolyzed at a temperature of 175° C. by the use of a bath tension of about 3 volts and with a cathodic current density of about 100 amp. per square centimeter.

The potassium-sodium alloy is then separated in the proportion of 77 per cent. potassium and 23 per cent. sodium. Immediately on being separated the metals are dissolved in the melt. After having attained the desired percentage of the alkali metals the melt is cooled to a temperature suitable for the reaction in which it is to be employed, provided the melt is made at the laboratory where it is to be used. If the melt is to be transported, the cooling is carried to the point of solidification.

If it is desired to produce a reducing melt containing more sodium than potassium this may be attained as follows:

Example II.

A melt consisting of 70 per cent. sodium hydroxid and 30 per cent. potassium hydroxid (melting point 240° C.) is electrolyzed at 246° C. by the use of a tension of about 3 volts and with the same cathode current density as in Example I. The alkali metals are then separated in the proportions of 71 per cent. of sodium and 29 per cent. of potassium.

In order to obtain the best possible proportion of the solution of alkali metals in the melt it is of advantage to use a low cathodic current density (1 to 0.01 amperes per square centimeter) and a high anodic current density (up to 50 amperes per square centimeter). By working with these melts which have a comparatively low melting point a good current output is attained. The current output may be further increased by working in vacuum, in an indifferent atmosphere or by protecting the melt with oils of a high boiling point.

In the drawing I have shown the electrolysis carried out in an iron vessel B, constructed as illustrated. The vessel contains a cathode K and an anode A insulated from the vessel, and the vessel is provided with a gas-tight cover C. The melt is heated by the internal current and the oxygen evolved escapes by one or both of the pipes P and R.

To further reduce the partial pressure of the oxygen in the space between the sur-

face of the melt and the cover C, this space may be exhausted, or an indifferent gas may be supplied through pipe P.

I claim:

- 5 1. A melt for use with organic substances having a low melting point, comprising an alkali hydroxid in which is dissolved metallic sodium and metallic potassium.
- 10 2. A melt for use with organic substances having a low melting point, comprising an alkali hydroxid in which is dissolved metallic sodium and metallic potassium in the proportion of one molecule of sodium to two molecules of potassium.
- 15 3. A melt of mixed alkali metal hydroxid containing metallic sodium and metallic potassium.
- 20 4. The method of producing an alkaline melt containing dissolved alkali metal for chemical reductions and syntheses, which comprises electrolyzing an alkali metal hydroxid melt.
- 25 5. The method of producing an alkaline melt containing dissolved alkali metal for chemical reductions and syntheses, which comprises electrolyzing a melt containing an equi-molecular mixture of sodium hydroxid and potassium hydroxid.

6. The method of producing an alkaline melt containing dissolved alkali metal for 30 chemical reductions and syntheses, which comprises electrolyzing a melt containing an equi-molecular mixture of sodium hydroxid and potassium hydroxid out of contact with the air.

7. The method of producing an alkaline melt containing dissolved alkali metal for 35 chemical reactions and syntheses, which comprises electrolyzing a metal of alkali metal hydroxid with a high anode current 40 density and a low cathode current density.

8. The method of producing an alkaline melt containing dissolved alkali metal for 45 chemical reductions and syntheses, which comprises electrolyzing a melt containing alkali metal hydroxid with an anode current density of from twenty to fifty amperes per square centimeter and a cathode current density below one ampere per square centimeter.

In testimony that I claim the foregoing as 50 my invention, I have signed my name in presence of two subscribing witnesses.

EINAR BERGVE.
